(57) **CLAIM**

The ornamental design for telephone headset, as shown and described.

DESCRIPTION

The patent or application file contains at least one drawing executed in color. Copies of this patent or patent application publication with color drawing(s) will be provided by the Office upon request and payment of the necessary fee.

1. Telephone headset

1.1 Left side

1.2 Top

1.3 Front

1.4 Bottom

1.5 Right Side

The design relates to a smartphone headset in the form of a pearl earring; the blue modeling clay in reproduction 1.5 forms no part of the claimed design; the reflections shown in reproduction 1.1 to 1.5 form no part of the claimed design. The portions of the article shown in broken lines form no part of the claimed design.

**1 Claim, 5 Drawing Sheets
(5 of 5 Drawing Sheet(s) Filed in Color)**
